(57) **CLAIM**

The ornamental design for a lid of an electrophoresis tank, as shown and described.

DESCRIPTION

FIG. 1 is a front, top and side perspective view of a lid of an electrophoresis tank, according to an exemplary embodiment;

FIG. 2 is a front view of the lid of the electrophoresis tank of FIG. 1;

FIG. 3 is a back view of the lid of the electrophoresis tank of FIG. 1;

FIG. 4 is a right side view of the lid of the electrophoresis tank of FIG. 1;

FIG. 5 is a left side view of the lid of the electrophoresis tank of FIG. 1;

FIG. 6 is a top view of the lid of the electrophoresis tank of FIG. 1; and,

FIG. 7 is a bottom view of the lid of the electrophoresis tank of FIG. 1.

The broken lines shown in the figures are included for the purpose of illustrating portions of the lid of an electrophoresis tank and form no part of the claimed design.
